J. A. LAMONT.
RAILWAY CAR TRUCK EQUALIZING ARRANGEMENT.
APPLICATION FILED DEC. 27, 1920.

Patented May 10, 1921.

UNITED STATES PATENT OFFICE.

JOHN A. LAMONT, OF CHICAGO, ILLINOIS, ASSIGNOR TO AMERICAN STEEL FOUNDRIES,
OF CHICAGO, ILLINOIS, A CORPORATION OF NEW JERSEY.

RAILWAY-CAR-TRUCK EQUALIZING ARRANGEMENT.

1,377,707.

Specification of Letters Patent. Patented May 10, 1921.

Application filed December 27, 1920. Serial No. 433,415.

To all whom it may concern:

Be it known that I, JOHN A. LAMONT, a citizen of the United States, residing at Chicago, in the county of Cook and State of Illinois, have invented certain new and useful Improvements in Railway-Car-Truck Equalizing Arrangements, of which the following is a specification.

This invention relates to railway car truck equalizing mechanism.

One object of the invention is to provide a simple, durable and efficient load equalizing arrangement for a railway car truck, and particularly those of the six-wheel type.

Another object is to provide an improved arrangement for transmitting loads to a journal, and particularly to an intermediate journal of a six-wheel truck.

These and other objects are accomplished by means of the arrangement disclosed on the accompanying sheet of drawings, in which—

Figure 1 is a fragmentary side elevation of a railway car truck embodying my invention;

Fig. 2 is a fragmentary longitudinal sectional view of the same arrangement; and

Fig. 3 is a sectional view taken in the plane of line 3—3 of Fig. 2.

The various novel features of my invention will be apparent from the following description and drawings and will be particularly pointed out in the appended claims.

The arrangement disclosed in the drawings is also disclosed in applicant's copending application, Serial No. 433,412 filed December 27, 1920, but is not claimed *per se* in such case.

Referring to the figures of the drawings of this present case, it will be noted that I have disclosed the invention in connection with a railway car truck including a side frame 10 having an opening 11 for the reception of a central journal box 19. This journal box has two laterally arranged pockets 20 on opposite sides of the center journal 21, the outer end walls 22 of which rise to a height to completely inclose the springs 23 located within the box 19. A spring cap 24 bridges the springs 23 on opposite sides of the journal 21 and is arranged to move vertically within the end walls 22 of the spring box. The spring cap 55 is provided with bosses 25 which extend

downwardly within the springs 23 for retaining the springs in place within certain predetermined limits. At each end of the spring cap and intermediate the projections 25, is an opening 26 for a purpose to be referred to hereinafter. The intermediate portion of the spring cap is provided with a curved seat 27 for rockably receiving a pivotal projection 28 on an equalizing beam 29. The outer ends of the equalizing beam 65 are bifurcated for the reception of eye portions 30 of hanger rods 31, the upper ends of which are pivotally connected to the ends of said equalizing beams by any suitable pins 32 located in the bifurcated portions 70 of said beam. These hanger rods extend vertically downwardly through the associated springs 23 and through openings 33 in the lower ends of the spring pockets 20. Each of the lower ends of the hanger rods 75 31 is provided with an eye portion 34 through which a key or pin 35 extends. Each hanger rod 31 extends through a vertical opening 36 in the associated end of an equalizing lever 37, the same end of each 80 of which is provided with a socket portion 38 in central alinement with its opening 36 and rests upon and receives the associated key 35 of the hanger rod whereby one end of each of the equalizing levers 37 is supported by a hanger rod, which in each instance is suspended from the equalizing beam 29 rockably supported upon the spring cap 24 which rests upon the springs 23 mounted in the central journal box 19. 90

As a result of this equalizing arrangement, the spring cap and equalizing beam serve to equalize the load between the center springs 23 and also equalize the load between the ends of the bolsters, not shown. 95 By using this equalizing beam 29 an even distribution to the four ends of the bolsters of the load on the center plate is insured. Without the use of the equalizing beam it would be possible for the bolster center plate 100 load to be concentrated on two, or possibly three, of the four legs. This equalizing beam instantaneously adjusts any difference in load on the four legs, which is caused by unevenness of the track, etc. Also in connection with the question of equalizing and movement of equalizing parts, attention is called to the fact that the lower ends of the hanger rods 31 in effect are the lower ends of pendulums, the lower ends, how- 110

ever, being stationary, while the upper ends swing in rounding a curve. In this way no lateral movement is given to the equalizing levers 37 or the bolster. A liberal allowance is made for relative lateral or sidewise movement of the center journal box with respect to the side frame for facilitating rounding curves.

Preferably the walls of the journal box 10 opening, or at least the lateral walls, are lined with wear plates 39 preferably in the form of steel plates.

It is my intention to cover all modifications of the invention falling within the 15 spirit and scope of the following claims.

I claim:

1. In a railway car truck, the combination of a journal box, springs carried by 20 said box on opposite sides thereof, a cap member bridging said springs, an equalizing beam movably mounted on said cap member, and hanger rods connected to said beam on opposite sides of its center whereby loads are transmitted and distributed to 25 said journal box.

2. In a railway car truck, the combination of a journal box, springs carried by 30 said box on opposite sides thereof, an equalizing beam operatively associated with said springs for transmitting loads therethrough, and hanger rods connected to said beam on opposite sides of its center whereby loads are transmitted thereto.

3. In a railway car truck, the combination 35 of a journal box, springs carried directly on said box on opposite sides thereof, and equalizing means operatively associated

with said springs for transmitting loads therethrough and equalizing the loads as between said springs.

4. In a railway car truck, the combination of a journal box, springs carried thereby, and an equalizing beam mounted on 40 said springs for transmitting loads therethrough to said journal box, said equalizing beam equalizing the loads as between said springs.

5. In a railway car truck, the combination of a journal box, springs carried by 45 said box on opposite sides thereof, means bridging said springs, an equalizing beam movably mounted on said bridging means, and means for transmitting loads through said equalizing means, bridge means and springs to said journal box.

6. In a railway car truck, the combination of a journal box, springs carried thereby, means bridging said springs, an equalizing beam pivotally mounted on said bridging means, and means for transmitting the loads 60 to said equalizing beam.

7. In a railway car truck, the combination of a journal box, springs carried by said box on opposite sides thereof, a cap member bridging said springs and having a seat portion, an equalizing beam having a rocker portion seated in said seat portion whereby loads transmitted to said equalizing beam will be transmitted and distributed to said journal box through said bridging member 70 and springs.

Signed at Chicago, Illinois, this 15th day of December, 1920.

JOHN A. LAMONT.
